UNITED STATES PATENT OFFICE.

HOWARD W. GOODALL, OF ALDAN, PENNSYLVANIA.

METAL-COVERED HOSE.

1,136,329.

Specification of Letters Patent. Patented Apr. 20, 1915.

Application filed November 8, 1913. Serial No. 799,987.

To all whom it may concern:

Be it known that I, HOWARD W. GOODALL, a citizen of the United States, residing at Aldan, Delaware county, Pennsylvania, have invented certain new and useful Improvements in Metal-Covered Hose, of which the following is a specification.

The principal object of the present invention is to provide a metal covered hose which shall be flexible and capable of short turns or bends and incapable of being kinked and in which the shape and arrangement of the wires of the metal cover not only impart strength and flexibility but also avoid cutting or abrasion of the tube or hose proper.

The invention will be claimed at the end hereof but will be first described in connection with the accompanying drawing which is a view, partly in section and partly in elevation, of a hose embodying features of the invention.

In the drawings 1, is a tube as of duck and rubber which may be an ordinary hose. 2 and 3, are a pair of half round rods or wires disposed one 3, with its flat face and the other 2, with its round face toward the surface of the tube 1. Each wire or rod is arranged around the tube in the form of a spiral having a pitch substantially equal to the width of the flat face of the other wire. The pitch of each spiral is substantially the same and the space formed by the pitch between the adjacent coils is shown at 4, and

this space 4, corresponds substantially in width with the width of the flat face of the rods or wires so that the space 4, between the adjacent coils of one spiral receives the coils of the other spiral.

The described half round form of the rods or wires prevents cutting or abrasion of the surface of the tube and also in connection with the spacing of the coils imparts flexibility to the article as a whole. Moreover, each wire or rod may contact with the face of the tube 1, so that strength and lightness are added to the above named advantages.

What I claim is:

A metal covered hose tube comprising the combination of a tube and a pair of substantially half round wires disposed one with its flat face and the other with its round face toward the surface of the hose tube said round and flat faces being flush and each in contact with the hose tube and each arranged around the tube in the form of a spiral having a pitch substantially equal to the width of the flat face of the other, substantially as described.

In testimony whereof I have hereunto signed my name.

HOWARD W. GOODALL.
